UNITED STATES PATENT OFFICE.

THOMAS TOWNSEND, OF PITTSBURGH, PENNSYLVANIA, ASSIGNOR OF ONE-HALF TO HARRY F. ANDERSON, OF MARION, INDIANA, AND ONE-HALF TO JAMES BOYCE, OF HOLLAND, MICHIGAN.

MACHINE FOR CUTTING DESIGNS, LETTERS, ETC.

Application filed July 8, 1924. Serial No. 724,793.

In the manufacture of illuminated signs, the outlines of letters, figures or designs are formed through some opaque material, generally sheet metal. It has heretofore been the practice to cut the outlines by means of shears, or if the metal sheet is thick, it has been necessary to employ cold chisels. As the outlines are, in part at least, irregular, there will be a bending of the edges of metal in turning the shears to form such irregular outlines, and when employing cold chisels, the edges of the sheet will be more or less bent. In the completed sign the edges of the opaque portion should be fitted closely against the glass sheet back of the opaque sheet, and hence it is the practice to flatten the sheet in a press or by pressing it between rolls after the outline has been formed, to eliminate the bends or kinks. But as the metal is more or less stretched when being bent by the shears or chisel, such rolling will only partially flatten the edges.

The object of the invention as described herein is to provide means whereby the outlines desired may be cut in a sheet without any bending or stretching of the metal. The invention is hereinafter more fully described and claimed.

In the accompanying drawings forming a part of this specification, Fig. 1 is an end elevation of the cutting mechanism claimed herein; Fig. 2 is an elevation of the opposite end of the mechanism; Fig. 3 is a top plan; and Fig. 4 is a rear elevation of the mechanism; and Figs. 5 and 6 are side and edge views of a cutter.

In the practice of the invention the cutter is not only driven but is also carried by an electric motor adapted to be shifted over the sheet operated on; the motor, which may be of any suitable construction, is enclosed in a suitable shell or casing 1 provided at its ends with bearings 2 for the shaft 3 of the armature. To facilitate the sliding of the motor over the sheet, and to maintain the axis of the armature substantially parallel with the sheet, a plurality of supports are provided. In the construction shown, three points of support are provided, two of such supports being in or approximately in alignment vertically with the axis of the armature shaft and the third support at one side of a line passing through the other two supports. One of said supports consists of a shoe formed by

a curved bar 4 having slotted fingers 5 at its ends and held in position by bolts 6 passing through the slots into the shell. The other shoe in alignment with the shaft of the armature consists of a bar 7 having a curved portion 8 and adjustably secured in position as hereinafter described. The third point of support is preferably formed by a roller 9 mounted in an extension of the handle 10 secured to one side of the shell or casing 1.

It will be apparent that by providing a support immediately adjacent the cutter and vertically beneath the cutter axis and a plurality of supports disposed from said first support axially of the cutter and adapted to permit movement of the tool transversely of the axis of the cutter, the tool may readily be pivoted about vertical axes intersecting the cutter axis. These shoes are adapted to permit movement of the tool transversely of its axis and to resist movement along the axis so that in pivoting the tool the cutter will roll peripherally in describing a curve rather than slide axially. With this construction it is possible to cause the cutter to describe curves of extremely short radii.

It will be readily understood by those skilled in the art that in order to readily cut along curved lines having short radii, the cutter should have comparatively small diameter and as the cutter should be so mounted that a portion of its edge will project below the supporting points, its axis of rotation is below the axis of the armature and hence provision is made for transmitting motion from the armature to the cutter. In the construction shown herein the cutter 11 is secured on a shaft 12 mounted in a boss 13 projecting from the cover 14 of a box 15. On the inner end of the shaft 12 is secured a pinion 16 adapted to intermesh with an idler 17, the journals of which extend into openings in the box and cover as shown in Fig. 4; this idler intermeshes with a pinion 18 secured on the shaft 3 of the armature, said shaft extending through the upper portion of the box. While the box may be secured to the shell or casing in any suitable manner, the construction shown has been found suitable and consists of arms 19 projecting laterally from the box and bolts 20 passing through the arms and screwing into the case or shell.

On the boss or projection 13 is secured a block 21 provided with a projection 22 over-

- hanging the cutter 11 secured as before stated on the shaft 12. To this overhanging portion 22 is secured one end of the bar 7 forming one of the supports of the mechanism. The curved portions 8 of this bar is slotted as at 23 permitting the lower portions of the cutter to project through and operate on the sheet. As before stated, the curved portion 8 bears on the surface of the sheet operated on and provision is made for adjusting the position of the portion 8 of the bar relative to the cutter and thereby regulate the depth of cut made by the cutter. Such depth of cut will vary in accordance with the thickness of gauge of the sheet operated on. The adjustment of the bar 7 can be effected in any suitable manner, as for example in the construction shown, one end of the bar 7 which is resilient, is secured to the portion 22 and the desired flexure of the free portion of the bar is effected by a screw 24 passing through the portion 22 and bearing on the bar as clearly shown in Figs. 1 and 3. In order to facilitate the manipulation of the mechanism, it is preferred to employ an auxiliary handle 25 preferably secured to the overhanging portion 22 so as to be in approximate alignment with the cutter. In the construction shown, the bar 7 is secured to the portion 22 by the handle, the threaded end of the latter passing through the up-turned end of the bar and screwing into the portion 22.
- As the outlines to be cut in a sheet have curved portions, the radii of some of such curved portions being small, the width of the cut should be greater than the thickness of the teeth in order that the cutter may be shifted to change the direction of cut. As shown in Figs. 5, 6 and 7, the teeth are approximately pyramidal in shape, the front and rear faces, *a* and *b* having equal inclinations. The sides *c* and *d* of the teeth are, however, differently inclined as clearly shown in Fig. 7. The side *c* of tooth *x* being at an obtuse angle to the side of the body of the cutter, while the side *d* of the tooth forms a more acute angle with the side of the cutter. The inclination of the sides of an adjacent tooth *y* are the reverse of those of the sides of tooth *x*. By reason of the described inclination of adjacent teeth, the apices will be out of line peripherally and consequently the cut made in the sheet will permit of such shifting of the mechanism as will permit the following of curved lines.
- It will be noted that the motor 1 constitutes the major portion of the framework of the machine and is of such size as to furnish the weight required to make the machine steady and free from objectionable vibration in the operation of the cutter. The parts 2, 3, 14, 15, 19 and 20 constitute frame means for supporting the cutter at a substantial distance from the motor. It will be understood

that in cutting a curve of short radius, the motor end of the machine is swung through a longer arc than if the cutter were close to the motor; consequently the motor end of the machine may be swung and guided with the required accuracy and precision more easily than if the arc was short. 70

In cutting a curve of larger radius, as, for example, one that extends toward the left in Fig. 3, the motor end of the machine would have relatively little movement of translation, the handle 25 being employed to push 75 the cutter end of the machine along the required path.

I claim herein as my invention:

1. A machine for cutting a metallic sheet comprising an electric motor which constitutes the major portion of the framework of the machine and furnishes the weight required for steadiness in operation, a relatively small rotary cutter frame means attached to the motor for supporting said cutter at a substantial distance from the motor, means for communicating power from the motor to the cutter, a support on said frame means adjacent to the cutter adapted to rest on the sheet being cut and adapted to permit the cutter to sever the sheet, a handle on said frame means adjacent to said cutter for guiding the cutter end of the machine when the latter is turning on the sheet, two supports on said motor adapted to rest on the sheet 95 being cut, said supports constituting a three-point support for the machine, permitting free turning movement of the machine on the sheet, and a handle on the motor for guiding the motor end of the machine in such turning movement. 100

2. A portable machine for cutting rigid sheet material comprising an electric motor which furnishes the weight required for steadiness in operation, a relatively small rotary cutter, frame means attached to the motor for supporting said cutter at a substantial distance from the motor, means for communicating power from the motor to the cutter, a support on said frame means adjacent to the cutter adapted to rest on the sheet being cut and adapted to permit the cutter to sever the sheet, a handle adjacent to said cutter for guiding the cutter end of the machine when the latter is turning on the sheet, two additional supports adapted to rest on the sheet being cut, said supports constituting a three-point support for the machine, permitting free turning movement of the machine on the sheet, and a handle for 115 guiding the motor end of the machine during such turning movement. 120

In testimony whereof, I have hereunto set my hand.

THOMAS TOWNSEND.
